BARRIER FOR RAILWAY LEVEL CROSSINGS AND THE LIKE

Application filed June 10, 1930, Serial No. 460,269, and in Argentina February 7, 1930.

Our invention refers to the equipping, in the safest way and in a simple and practical manner, railway level crossings in the neighbourhood of the city and camp where 5 accidents occur with sufficient frequency, some with fatal consequences when the loss of life is to be lamented, and abundant material damages result.

The present invention consists of barriers that function automatically on the passing 10 of locomotives or trains, thus obviating the necessity of barrier guards; these barriers also solve one of the most difficult problems existing up to the present which is the 15 security of level crossings of so many places which by reason of the distance, remain without any sort of care.

The invention has equally in view other objects which will be made clear in the course 20 of the present specification and which will be set forth in the appended claims.

In order that this invention may be clearly understood and easily put into practice, an example is given of the most practical form 25 of operation in the annexed drawings, wherein:—

Figures 1 and 1(a) are views of the entire arrangement.

Figure 2 represents a sectional arrangement 30 of the whole mechanism.

Figure 3 represents the entire levers that can be used in substitution of the arrangement shown in Figure 2.

Figure 4 is a front view of the arrangement 35 of levers for the inverse movement.

Figure 5 represents a type of hand-lever that can be utilized in substitution of the previous arrangements.

Figure 6 is a detail of the pin which is fixed 40 to the cow-catcher of the engine, for the purpose of operating the signal arrangement; and finally:—

Figure 7 represents the hydraulic counter-weight for facilitating the gradual closing 45 of the barriers.

In order to give a better idea of the arrangement which is the object of this invention, reference is made first of all to the entire installation represented by Figures 1 50 and 1(a).

The arrangement consists of the barriers *a*—*c* which rest on the supports *M* at the points *B*, and when they are in a closed position their end "*a*" rests on another support *R*. Both the supports *M* and *R* are conveniently fixed in the ground as will be shown hereinafter. The supports *M* are formed by two pieces of iron of equal height and shape suitably separated from one another and connected by means of the pins *A*₃. The said supports are fastened to the ground by screws through special bases made of material most suitable for the purpose or in accordance with the nature of the soil. In the form shown three pins have been adopted, one principal and two auxiliaries. Other pins are provided *A*—1 and *A*—2 where the levers *L* and *S* are fixed in both support plates, which serve to operate the pillion or running balance-counterweight *T* situated in the afterpart *b*—*c* of the barrier. The pillion *T* should be made of the material most suitable. The two levers *S* corresponding to the same support are connected below the latter by means of a transverse axle *A*—4, *A*—4', at the 55 central point of which, *A*—5, is connected a control bar *N* sustained by the supports *V* of suitable size or dimension. This bar *N*, of suitable length, is utilized for transmitting the pulling movement to the levers *L* and *S*. Both ends of the bar *N* are joined to the levers *Z* at the points *C*—3 and *C*—3'. The said bar *N* is arranged in a subterranean channel. The last mentioned lever is sustained by its point *C*—1 rotatively on the support *P*. At 60 the other end *C*—2, the lever *Z* is joined to the bar *Q* sustained by the supports *V*—1. The said lever *Z* is utilized, as will be seen hereunder, for operating the bars *N* and *Q*. The unions *C*—1, *C*—2 and *C*—3 are effected by 65 means of pins, with a view of facilitating the rotation of the parts. Both rods *N* are connected by an axle *W* that runs below the line transversely, effecting thus the union between the parts by means of the eccentrics *D*—1. The transmitting transversal axle *W*, of suitable length, shape and dimensions, is disposed below the ground and is sustained by the supports *G*. This axle is that which effects the 70 transmission of the same movements to both 75 80 85 90 95 100

barriers through the bars N which in turn operate the levers S and L.

The rod Q articulates through its ends E-3 and E-3' with the essential parts of the apparatus; the automatic movements of the barriers are produced through the medium of this bar.

At E-3 the lever X₁ articulates, as is clearly shown in Figure 1(a), to which lever is attached the lever X to the other end of which is attached the piece T-2. Suitably fitted to the line, as will be shown later on, is an arrangement formed by the part U inversely placed in the soil and which carries the cross-bars "n" and "l".

The parts "n" and "l" are perforated in order to permit of the passage of axles "r" which carry at their large end some triangular pieces "h" and "h'" of iron, or similar material, which are provided with lateral plugs "p" and "p'" that operate or work in connection with the parts T-2 mentioned above.

The said barrier proper a-c consists of two parts: one of them a-b should preferably be of wood, and the other b-c preferably of iron, its length being such that may be found most convenient.

When the barriers are closed they rest on the supports R, which latter may be manufactured of iron or wood fixed in the soil and whose upper parts should be made in the form of a fork, the size being that which is most convenient.

Figure 2 represents the arrangements formed by a U-shaped piece "m" where in the perforated cross-bars n and l are fitted the triangular pieces h and h' made of iron or similar material, provided with plugs p and p' that operate the part T-2, the dimensions being those which may be found necessary; these parts are suitably fitted near to the line and rest on the sleepers or on the special bases, according to the necessities of the case, and being held thereto by means of screws or clamps.

Figure 3 shows a set of movable levers which can be substituted for the arrangement shown in Figure 2. This arrangement, as will be seen, is formed by an elbow-arm which by means of a pin E³ operates the bar Q; the said arm is joined to an iron-bar F of suitable dimensions, which has in its lower part a counterweight that enables it to always maintain a vertical position and is sustained by two supports F'. At F-2 the lever F-3 is connected by an axle to the lever F and the upper part of the lever F-3; at F-4 through the medium of a pin, is attached the bar F-5 which transmits the movement by the pin F-6 to the lever F-7. This last mentioned lever rests on the support F'' fixed with screws to the sleepers or adequate bases as in the case of the support F'. Figure 4 represents a movable lever provided with the pin E-3' which operates it or on a governor

rod Q and produces the inverse movement of the lever.

Figure 5 represents, as stated above, a hand-lever that can be substituted for the automatic movements of the pieces shown in Figures 2, 3 and 4. It is constructed entirely of iron and has attached to it a safety crotch, which runs over a sector provided with clutches H and H', the said lever being coupled to the sector at H-3 by a pin; the said sector should be fixed on special bases. At H-3 there is attached a small lever which operates the safety crotch.

Figure 6 represents the steel pin which is attached to the cow-catcher of the engine (the only attachment that is carried by the locomotive for the automatic operation of the barriers); this pin is attached to the cow-catcher by means of the screws I', I'' and at its terminal it carries a roller I''' which serves the purpose of colliding with the apparatuses of the automatic movements or arrangements.

Operation

The parts h and h' are placed close to the track, one in active or elevated position in relation thereto and the other below the track. On the passing of a train whose locomotive is provided with a special part for that purpose, said part collides with the piece h or h'. As in Figures 1 and 1a closed barriers are shown, we will now describe the operation for the automatic opening of the same. When passing, the train depresses the piece h' which through its plug p' acts on the left wing (in accordance with Figure 1) of the part T-2 by which movement the bar Q is pulled and this through the medium of the lever Z actuates the bar N. As the latter is attached to the other bar N opposite, by means of the lever W, both bars N follow the same movements. The bars N operate the levers S through the axles A-4 and A-4'. The lever S operates the lever L causing the sliding of the counterweight T towards the end "c", by which action the barriers are raised. It is thus easy to understand how the closing is effected.

The operation of the barriers by means of the arrangements composed of the triangular pieces h, h' has been explained. By means of the levers shown in Figs. 3 and 4, the same movements can be produced, when the pin, shown in Figure 6 and carried on the cow-catcher of the engine, collides with the forwardly inclined bar of the levers shown in Figures 3 and 4, whereby the bar Q is pulled resulting in the series of movements mentioned above which cause the opening of the barriers. The opening and closing movements of the barriers can be effected by a man by means of a hand-lever which can be utilized close to villages and cities.

For closing the barriers, one of the above described arrangements or automatic levers is

provided with a double accentric or double set of levers that produces the inverse movement.

The apparatuses described above are intended for a single-line track; in case of a double track the apparatuses referred to for single-track working should also be placed on the other track and operated with the same barriers and in the same manner.

10 It is evident that various modifications in construction and in detail can be introduced without departing from the principle of the present invention which is clearly set out in the undermentioned clauses of claims.

15 We claim:—

1. In combination with a railroad track, two spaced supports provided on each side of the track, barriers pivotally carried by said supports and provided each with a rearwardly extending portion, a weight slidably mounted on said portion, an arm pivotally connected to said weight for moving the same in either direction, a lever pivoted intermediate its ends on said support and articulated 25 to said arm, a horizontally movable bar operatively associated with said lever, triangularly shaped members provided near the track and adapted to be depressed by a part carried on the locomotive of a train, and means intermediate said triangularly shaped members and said bar for transmitting therethrough a corresponding movement to said lever and said arm to thereby shift said sliding weight in either direction for automatically closing 30 or opening the barrier.

2. The combination as specified in claim 1, including a control bar operatively associated with said horizontally movable bar, centrally pivoted members linked to said control bar 40 and adapted to be rocked about their pivots by plugs provided on said triangularly shaped members to thereby exert a pull on said control bar in either direction, said pull being transmitted to said horizontally movable bar.

3. The combination as set forth in claim 1, including a transverse axle operatively connecting the horizontally movable bars on either side of the track.

50 In testimony whereof we affix our signatures.

LAZARO MIGUEL CAMPODONICO.
LUIS BARATELLI.
